UNITED STATES PATENT OFFICE.

JOHN W. BLOCK, OF JOLIET, ILLINOIS.

PULVERIZER.

937,411.

Specification of Letters Patent. Patented Oct. 19, 1909.

Application filed January 25, 1908. Serial No. 412,609.

To all whom it may concern:

Be it known that I, JOHN W. BLOCK, a citizen of the United States, residing at Joliet, in the county of Will and State of Illinois, have invented a new and useful Pulverizer, of which the following is a specification.

My invention relates to grinding mills and especially to the rotary type of machines used for pulverizing or reducing various substances to a highly comminuted or powdered condition, such apparatus being classified as rotary beater machines.

In the reduction of materials to a powdered state considerable difficulty is experienced in producing the required result when certain organic substances, such as grains, are undergoing treatment, owing to the tendency, in some cases, to the formation of lump and masses by reason of the glutinous or adhesive constituents of the material, and in all cases it is necessary to provide means for preventing the discharge of the larger particles with the more highly comminuted portions. The accumulation of moisture is another disadvantage commonly met with in the process under consideration.

The chief objects sought by the improvements which form the subject matter of this application are:—to provide an apparatus for the purpose stated that will be simple in construction, efficient in its operation and that will have an unusually rapid effect upon the substances submitted to its action, resulting in their becoming thoroughly comminuted, blended and aerated, the finished product being of a high grade.

Stating certain objects more in detail, the apparatus hereinafter disclosed is designed to produce a continuous feed of the material to be powdered and mixed; to intermingle with the substance treated a stream of air having the double function of creating a current by means of which the treated substances will be carried to the operating mechanism and thereafter transferred beyond the operating chamber, and also aerating the comminuted materials, thereby removing surplus moisture, and preventing fermentive and other chemical changes to which certain classes of substances are liable during the process of grinding.

I accomplish the above and other minor objects by means of the apparatus illustrated

in the accompanying drawing, forming a 55 part of this application, and in which:—

Figure 1 is a vertical section of the preferred form of my improved pulverizer; Fig. 2 is a top plan view of the machine with the driving pulley removed, and Figs. 60 3 and 4 are sectional views on the lines 2—2 and 3—3 respectively, of Fig. 1.

Referring to the details of the drawing, the reference character *a* indicates a casing in the form of a truncated cone, and supplied with a cone-shaped cover *b*, from the center of which rises a dome *b*¹ having a side outlet *h* connected in any suitable manner, with an exhaust fan (not shown in the drawing). The casing *a* rests upon a bottom plate *c*, and this in turn is supported upon a cylindrical base *c*¹, supplied with air inlet ports *c*². From the under side of the bottom *c* projects a hollow extension communicating at one end with the interior of the casing *a*, through a centrally located circular opening *c*⁴ and at its other end with the chamber *c*¹.

Near its bottom the casing *a* has a hollow cylindrical extension *d* in which is journaled a screw conveyer *e*, while above the extension is fixed a feed hopper *g*. Concentric with the said casing is a vertical shaft *j*, extending entirely through the casing at both ends, its foot having a bearing in a step *j*¹, supported in a hanger *j*², suspended from the extension *f*. Near its upper end the said shaft is journaled in a box or bearing *j*³, supported upon the dome *b*¹, and upon its projecting extremity is keyed a driving pulley *j*⁴.

Mounted upon the said shaft *j*, within the casing *a*, is a hollow cone or receptacle *i* having its sides parallel with the said casing *a*, and separated therefrom by an annular space *a*¹. This inside cone *i* is open above 95 and has a bottom *i*¹, furnished with radially extending channels *k*, which communicate with the annular space *a*¹. The outer surface of the receptacle or cone *i* is studded with a number of wings or beaters *m*, in the form of flattened vanes or blades secured by threaded stems *m*¹, which pass through the wall of the receptacle *i*, and are firmly secured by nuts. This arrangement permits the blades *m* to be placed at various angles, 100 which is of special advantage since it is desirable to vary the inclination of the blades of the beaters according to the character of

the substances undergoing treatment. Within the said inside cone or receptacle i , is suspended a stationary cone-shaped hopper n , which is attached to the cover b by hangers n^1 . The said hopper has a greater flare than the surrounding revolving drum and is open at both ends. The lower contracted end closely surrounds the hub i^2 of the cup-shaped receptacle i , but does not come in contact therewith, a comparatively narrow annular space n^2 being left between the said cone and hub, forming a communication between the cavities of the fixed hopper and movable receptacle. Upon the shaft j between the bottom i^1 of the inside cone and the bottom plate c of the casing a , is mounted a collar p^1 , which supports a number of radial arms or hammers p , pivoted to swing or oscillate horizontally to a limited extent upon pins q which extend through both collar p^1 and the bottom i^1 of the cone i , and are removable. The free ends of the said arms are flattened vertically to form hammer-heads p^2 , and extend to near the inner wall of the casing a , only sufficient space being left between the hammers and the casing to give proper clearance.

The method of operating the pulverizing apparatus hereinbefore described is as follows:—The pulley j^4 having been connected with any available source of power the upright shaft j is rapidly rotated, causing a swift revolution of the drum carrying the beaters m , and also the swinging hammers p . By means of a pneumatic exhaust fan, (previously mentioned but not illustrated) attached to the outlet h of the cover dome b^1 , a strong current of air is maintained throughout the various communicating passages and cavities of the apparatus, taking a course as follows:—The air first enters the base c^1 through the ports c^2 and finds entrance into the casing a by the passage f and opening c^4 , where it encounters the swinging hammers p , and ascending through the annular space a^1 , between the cone i and the casing a , finally escapes through the outlet passage h in the dome b^1 and is then led to any desired locality. The material to be ground or pulverized is fed into the hopper g , and by the screw conveyer e is forced into the casing a where it meets with the current of air which tends to carry said material upward. The material however, is usually fed in such a condition that the particles and masses are too heavy to be materially affected by the air current, and must first be reduced to the proper condition, so that the gravity of the substances may be sufficiently reduced to permit of their flotation. This reduction is accomplished by the action of the swiftly revolving arms p and hammer-heads p^2 which beat and strike the heavier particles until they are sufficiently comminuted to permit the action of the current to carry the pulver-

ized substances upward through the confined space a^1 , where the revolving beaters continue the disintegrating and blending process, so that by the time the material laden current has reached the greater space directly beneath the cover, some of it will have become sufficiently light to be carried onward through the outlet port with the escaping air but as the velocity of the current is lessened in the more expanded space above the annular passage a^1 the heavier particles will fall by gravity and being collected by the fixed chute or hopper n will pass through the annular space n^2 and be carried by the centrifugal force through the channels k meeting the ascending current to be again subjected to the action of the numerous beaters m . The heavier particles are thus being continuously driven upward, subjected to the action of the beaters and allowed to fall and again brought into contact with the beaters until the entire mass has been reduced to a sufficiently comminuted state to permit of its being carried away through the proper channels.

The action of the hammers is of special advantage, since their pivotal attachment to the upright shaft permits them to rebound somewhat when meeting with unusual resistance, and as the substances to be pulverized are frequently fed to the machine in comparatively large and hard pieces not readily reduced by a single direct blow, this arrangement avoids the tendency to severe shocks which would be likely to break or otherwise damage the mechanism. The current of air is prevented from finding an exit through the extension d by keeping the conveyer well filled with material so as to act as a valve.

While the housing or casing as well as the revolving cone or receptacle have been shown of conical form this shape is not essential to the proper working of the apparatus. It is obvious that other changes may be made in the devices of my invention without departing from the spirit and scope thereof, and I do not wish, therefore, to be limited to the precise construction set forth.

When the grinding material is of moderate density or the substances supplied have received a preliminary crushing so as to render the particles lighter, the swinging hammers may be detached, the pivots being made removable for that purpose and the beaters m alone depended upon to produce the pulverizing. The adjustability of the vanes or beaters, will permit the blades to be placed at an incline to the horizontal plane, and as they are rapidly revolved they will create a strong current of air, thus supplementing the effect of the current-generating device or exhauster and this result may be sufficient to accomplish the transmission of lighter grades of material through the

machine so that the pulverizing process may be completed without the employment of an exhaust fan.

Having thus described my invention, what I claim as new, is:—

1. In a pulverizer, the combination with a casing provided with an air inlet and outlet ports and means for introducing material to be pulverized into the said casing, said means arranged at the bottom of the casing, of a rotatable drum mounted within the casing and having discharge conduits near its bottom, and beaters projecting radially from the drum.
2. In a pulverizer, the combination with a casing provided with axial air inlet and outlet ports, feed means communicating with the lower part of said casing, a rotatable receptacle in the casing, said receptacle having discharge conduits near the bottom, beaters projecting radially from the receptacle, and a hopper inclosed by said casing and spaced therefrom, said hopper adapted to discharge into said receptacle.
3. In a pulverizer, the combination with the casing, having air inlet and outlet ports, of a rotatable receptacle in the casing and having radial channels in its bottom, of a drum arranged within the casing, and communicating therewith and with the receptacle, and beaters projecting from the said receptacle.
4. In a pulverizer, the combination with a casing having air inlet and outlet ports, and a shaft concentric therewith, of a receptacle rotatable in said casing, pivoted arms rotatable with said shaft and extending horizontally within said casing, and beaters fixed on said receptacle, said receptacle having communication with the casing at its top and bottom.
5. In a pulverizer, the combination with a casing having air inlet and outlet ports, and a shaft concentric therewith, of a receptacle mounted upon the shaft in the casing, discharge conduits in the bottom of said receptacle communicating with the said casing, beaters extending laterally from the receptacle, arms carried by the shaft and arranged below the receptacle, and a fixed hopper arranged partly within said receptacle and partly within said casing and having communication with both casing and receptacle.
6. In a pulverizer, the combination with a casing, having air inlet and outlet ports, and a shaft concentric therewith, of a receptacle

mounted upon the shaft within the casing, discharge openings in the bottom of said receptacle communicating with the casing, a plurality of adjustable beaters projecting from the receptacle, arms pivotally connected to said shaft and a fixed hopper arranged within the casing and communicating with the receptacle and the casing.

7. In a pulverizing mill comprising a casing having a central air inlet port at its bottom, a central discharge port at its top, and means for feeding into the casing the material to be pulverized, pulverizing means comprising a rotatable drum having rigid beaters secured thereto, and other beaters swingingly mounted on said drum, and means for driving said drum.

8. In a pulverizing mill comprising a casing having a central air inlet port at its bottom, a central discharge port at its top, and means for feeding into the casing the material to be pulverized, pulverizing means comprising a rotatable drum having rigid beaters adjustably secured thereto, and other beaters swingingly mounted on said drum, and a hopper within said casing and communicating with said drum.

9. In a pulverizing mill, comprising a casing having suitable air inlet and outlet openings, a rotatable drum open at the top and having discharge openings in its bottom, a chute fixed in said casing and discharging into said drum at the bottom, beaters secured to said drum, and means for feeding material into the bottom of the casing and means for conveying the pulverized material from the top of said casing.

10. In a pulverizer, a casing having inlet and outlet for air and material to be pulverized, an inverted frusto-conical chute fixedly arranged within said casing with an annular space between the top of the chute and the walls of the casing, a receptacle rotatably mounted within the casing and adapted to receive material from the chute and discharge it into the casing, beaters rotatably mounted in said casing, and means for feeding material into said casing.

In testimony whereof I have signed my name to this specification in the presence of two subscribing witnesses.
